FIG. 1

FIG. 2

FIG. 3

FIG. 4

FIG. 5

FIG. 6

FIG. 1 is a side view of the wall mounted shoe shine apparatus showing my new design, the opposite side having the same appearance;

FIG. 2 is a front view of the wall mounted shoe shine apparatus of FIG. 1;

FIG. 3 is a top view of the wall mounted shoe shine apparatus;

FIG. 4 is a bottom view of the wall mounted shoe shine apparatus of FIG. 1;

FIG. 5 is a perspective view of the wall mounted shoe shine apparatus of FIG. 1; and

FIG. 6 is an enlarged view of a portion of the surface of the platform of the wall mounted shoe shine apparatus of FIG. 1.

The rear of the apparatus is unadorned and unornamented, and when installed on the wall is hidden from view.

I claim:

The ornamental design for a wall mounted shoe shine apparatus, as shown and described.
